COMBUSTION CHAMBER WITH RETRORE
BAFFLES FOR PREHEATING THE FUEL-
AIR MIXTUREWilliam B. Gist, Jr., Crum Lynne, Pa., assignor
to Westinghouse Electric Corporation, East
Pittsburgh, Pa., a corporation of Pennsylvania

Application October 25, 1949, Serial No. 123,437

8 Claims. (Cl. 60—44)

1

This invention relates to combustion apparatus, and more particularly to liquid fuel combustion apparatus for a gas power plant or the like.

In operation of combustion apparatus in a gas turbine engine, atherdyd or the like, it is desirable to effect mixture of atomized fuel with air and rapid preheating of the mixture immediately before combustion thereof, for ensuring greater combustion efficiency and flame stability. Preheating of the fuel is usually a critical operation, due to the tendency to induce cracking of the fuel, and deposition of carbon on surfaces of the burner. It is an object of this invention to provide improved combustion apparatus constructed and arranged to effect rapid vaporizing and preheating of fuel and air without cracking or deposition of carbon.

Another object of the invention is the provision of combustion apparatus adapted to promote the efficient and stable combustion of fuel in a power plant under operating conditions that induce relatively low fuel pressures and rates of air flow.

A further object is to provide combustion apparatus, in which stable combustion of fuel can be effected quickly enough to warrant reduction in length of the combustion chamber relative to that heretofore believed necessary.

Features of the invention include the provision of an improved combustion assembly of relatively inexpensive lightweight construction, in which interposition of structural elements directly in the flame zone is avoided, and in which flow communications and orifices are adapted to ensure uniform vaporization and combustion of fuel with minimum interference due to occasional presence of foreign particles in the fuel.

These and other objects are effected by the invention as will be apparent from the following description and claims taken in connection with the accompanying drawing, forming a part of this application, in which:

Fig. 1 is a diagrammatic view, partly in section, of a gas turbine engine having combustion apparatus constructed in accordance with one form of the invention;

Fig. 2 is an enlarged detail, sectional view of a portion of the combustion apparatus shown in Fig. 1; and

Fig. 3 is a fragmentary sectional view taken along the line III—III of Fig. 2, and indicating the section line II—II along which the latter is taken.

The essential elements of a typical aviation gas turbine power plant are illustrated diagram-

atically in Fig. 1, and comprise an outer casing structure 11, which may be made up of a number of cylindrical sections and which has suitably mounted therein an inner sectional core structure 12 cooperating with the outer structure to form an annular flow passageway 13, which extends longitudinally through the engine from a forwardly-directed intake opening 14 to a rearwardly-disposed discharge nozzle 15. It will be understood that the casing structure 11 is adapted to be mounted in or on the fuselage or wing of an aircraft, with the inlet opening 14 pointed forwardly. Operating elements of the gas turbine engine are arranged in axial alignment in order to minimize the frontal area presented by the engine, and include an axial-flow compressor 19, combustion apparatus 20, illustrated in annular form, and a turbine 21, which is operatively connected to the rotor of the compressor through the medium of an axially disposed shaft 22.

In accordance with well-known principles of operation of gas turbine power plants, air entering the annular intake opening 14 passes to the compressor 19, which delivers the air under pressure through the passage 13 to the combustion apparatus 20 for supporting combustion of fuel, which may be admitted by means hereinafter described. Heated motive fluid thus generated in the combustion apparatus 20 is then expanded through the turbine 21 for driving the compressor, while the exhausted motive fluid is discharged to the atmosphere by way of the nozzle 15, and may be in the form of a jet establishing a propulsive thrust.

According to the invention, the combustion apparatus may be of the unitary annular type, or may if preferred include a plurality of separate combustor chambers or "cans." In the annular form chosen for illustration, the combustion apparatus 20 comprises an outer annular burner wall 25, which may be an assembly of overlapped graduated sections forming air inlet slots or apertures 26 communicating with an interior combustion chamber 27, and an inner annular burner wall 28, consisting of similarly arranged sections providing air inlet slots 29, the wall assembly being supported from the casing structure 11 by suitable struts, such as a hollow strut 30. Mounted within the frontal annular entryway 21a of the combustion chamber 27 are two radially spaced outer and inner annular substantially U-shaped channel sections 33 and 34, which may be supported on the strut 30 with the concave surfaces thereof facing in an upstream direction while the opposite sides thereof are exposed within the

combustion chamber 27. Each of the channel sections 33 and 34 has a short annular side *a*, which may be secured to the adjacent end of the corresponding burner wall 25 or 28, and a relatively long side *b*, which may be generally frusto-conical in form and extends forwardly, as shown. A pair of outer and inner frusto-conical flow divider baffle structures 36 and 37 are also carried on the strut 30 in spaced alignment with the respective channel sections 33 and 34, further enclosing the annular entryway 27a of the combustion chamber, and carrying an annular foraminous wall or baffle 38 having apertures spaced for slightly impeding flow of air from the passageway 13 to the entryway 27a, for a purpose herein-after explained. The respective flow divider baffle structures 36 and 37 have mounted in the rear-most portions thereof outer and inner fuel manifolds 40 and 41 which communicate through pipes 40a and 41a with a suitable fuel system (not shown). The manifolds 40 and 41 are adapted to supply fuel into curved annular preheating passages 42 and 43, respectively, by way of suitable ejecting means, such as circumferentially spaced nozzles or orifices 45 formed in the downstream sides of the manifolds.

In operation, as air delivered by the compressor 19 flows from the passageway 13 through the foraminous baffle 38 into the entryway 27a of the combustion chamber, the impedance effect of the baffle 38 produces a local zone of relatively low air velocity and pressure on the downstream side thereof, increasing turbulence within the entryway, and causing air to be drawn inwardly from the passageway by way of the curved preheating passages 42 and 43, picking up and vaporizing fuel issuing from the orifices 45. In practice, for example, eight or nine pounds of air flowing through the baffle 38 for each pound of fuel supplied by way of the manifolds 40 and 41 may be expected to induce flow of about five pounds of air per pound of fuel through the preheating passages 42 and 43. As the air in the preheating passages pivots around the manifolds and reverses in direction of flow toward the zone of local turbulence and low pressure, the fuel sprayed across the air stream onto the hot channel sections 33 and 34 is vaporized and swept along quickly enough to prevent cracking of the fuel and deposition of tars or carbon.

With the fuel thus vaporized, the heated fuel and air mixture is swept out of the respective preheating passages 42 and 43 into the turbulent zone or entryway 27a and into the combustion chamber 27, where combustion is further supported by air entering by way of the apertures 26 and 29. The air-fuel ratio in this zone should be slightly richer than stoichiometric. The dimensions of the combustion chamber are preferably such as to promote relatively low air velocity, and consequently, a stable flame zone. Heat from the combustion zone serves to maintain the channel members 33 and 34 sufficiently hot to continue vaporization of incoming fuel.

It will further be seen that the improved combustion apparatus, constructed and operated as hereinbefore described, will ensure uniform vaporization and combustion of the efficiently preheated fuel in such a manner as to render the power plant operable with any of a wide range of fuels, including relatively inexpensive, commercially available fuels having high boiling points, such as kerosene.

While the invention has been shown in but one form, it will be obvious to those skilled in the

art that it is not so limited, but is susceptible of various changes and modifications without departing from the spirit thereof.

What is claimed is:

1. In combustion apparatus including an annular combustion chamber and an annular air supply passage communicating therewith; annular fuel manifold means mounted upstream of said combustion chamber and having fuel discharge orifices, wall means establishing separate flow paths in said passage on opposite sides of said manifold, an annular retrorse baffle mounted between said combustion chamber and said manifold and forming a preheating passage having an air entryway communicating with one of said flow paths and an air outlet communicating with said other flow path, and flow impeding baffle means interposed in the last-mentioned flow path for effecting reduction in air pressure at said air outlet for establishing a current of air through said preheating passage to pick up and vaporize fuel from said manifold in initial heat exchange relation with said baffle, prior to flow of the heated air and fuel mixture into said combustion chamber.

2. In combustion apparatus including an annular combustion chamber and an annular air supply passage communicating therewith; spaced concentric inner and outer annular fuel manifolds mounted upstream of said combustion chamber and having fuel discharge orifices, wall means establishing separate outer flow paths in said passage outwardly of said manifolds and a central flow path therebetween, concentric annular re-entrant baffles subject to heat of combustion in said combustion chamber and spaced downstream of said manifolds, respectively, each of said manifolds having means for effecting the spraying of fuel onto the respective baffles for abstracting heat therefrom, and a foraminous baffle interposed in said central flow path for effecting local turbulence and reduction in pressure of air inducing continuous flow of air from said outer flow paths to sweep the sprayed and heated fuel into said combustion chamber.

3. Combustion apparatus comprising substantially cylindrical wall and core structure forming an annular air supply passage, inner and outer apertured combustor walls mounted in spaced coaxial relation in said passage for providing an annular combustion chamber having an upstream entryway, concentric inner and outer annular channel members mounted adjacent the respective combustor walls and having concave surfaces facing upstream and terminating within said entryway, said channel members being subject to heat from said combustion chamber, fuel supply means aligned with the concave surfaces of said channel members and spaced upstream thereof, and means interposed in the path of air flowing from said supply passage into said entryway for effecting reduction in air pressure in said entryway, thereby inducing flow of air from said passage past said fuel supply means and said channel members for rapidly mixing fuel and air with initial transfer thereto of heat from said channel members prior to flow thereof into said combustion chamber.

4. Combustion apparatus comprising substantially cylindrical wall and core structure forming an annular air supply passage, inner and outer apertured combustor walls mounted in spaced coaxial relation in said passage for providing an annular combustion chamber having an upstream entryway, concentric inner and outer an-

nular channel members having substantially U-shaped cross sections and mounted adjacent said combustor walls, respectively, in heat transfer relation with respect to said combustion chamber, spaced concentric annular flow dividing baffle structures supported in said air supply passage and terminating in fuel manifolds having discharge orifices disposed upstream of the respective channel members, said baffle structures and corresponding channel members forming curved annular preheating passages communicating with said air supply passages and discharging into said entryway, and an annular apertured baffle extending across the space between said baffle structures upstream of said entryway, whereby flow of air from said supply passage to said entryway is throttled to effect reduction in pressure in the latter for drawing air thereto from said supply passage through said preheating passages along with vaporized fuel from said manifolds.

5. Combustion apparatus comprising boundary wall structure providing an air supply passage, interior wall structure disposed therein and forming a combustion chamber, a fuel manifold mounted upstream of said combustion chamber and having fuel discharge orifices, and a curved re-entrant baffle interposed between said combustion chamber and said fuel manifold, said baffle and manifold forming a preheating passage having an air entryway communicating with said air supply passage and an outlet communicating with said combustion chamber, whereby a path for air is established through said preheating passage for effecting vaporization of fuel discharged from said manifold in initial heat exchange relation with said baffle prior to flow of the heated air and fuel mixture into said combustion chamber.

6. In combustion apparatus including an annular combustion chamber and an annular air supply passage communicating therewith; spaced concentric inner and outer annular fuel manifolds mounted upstream of said combustion chamber and having fuel discharge orifices, wall means establishing separate outer flow paths in said passage outwardly of said manifolds and a central flow path therebetween, and concentric annular re-entrant baffles subject to heat of combustion in said combustion chamber and spaced downstream of said manifolds, respectively, each of said manifolds having means for effecting the

spraying of fuel on the respective baffles for abstracting heat therefrom, whereby air flowing from said outer flow paths is mixed with fuel and preheated during contact with said baffles prior to delivery to said combustion chamber along with air from said central flow path.

7. Combustion apparatus comprising boundary wall structure providing an air supply passage, interior wall structure disposed therein and forming a combustion chamber, a fuel manifold mounted upstream of said combustion chamber and having a fuel discharge orifice, a curved re-entrant baffle interposed between said combustion chamber and said fuel manifold to provide a preheating passage from said air supply to said combustion chamber, and an auxiliary duct structure having flow-limiting passages disposed within said boundary wall structure and extending upstream with respect to said baffle for effecting supply of air at reduced pressure from said air supply passage to said combustion chamber adjacent the outlet end of said preheating passage, whereby air is caused to flow through said preheating passage to sweep vaporized fuel into said combustion chamber.

8. Combustion apparatus comprising substantially cylindrical wall and core structure forming an annular air supply passage, inner and outer apertured combustor walls mounted in spaced coaxial relation in said passage for providing an annular combustion chamber having an upstream entryway, concentric inner and outer annular channel members having substantially U-shaped cross sections and mounted adjacent said combustor walls, respectively, in heat transfer relation with respect to said combustion chamber, and spaced concentric annular flow-dividing baffle structures supported in said air supply passage and terminating in fuel manifolds having discharge orifices disposed upstream of the respective channel members, said baffle structures and corresponding channel members forming curved annular preheating passages communicating with said air supply passages and discharging into said entryway, whereby flow of air from said supply passage to said entryway is throttled to effect reduction in pressure in the latter for drawing air thereto from said supply passage through said preheating passages along with vaporized fuel from said manifolds.
